FIG. 2

INVENTOR

WILLIAM L. GILCHRIST

BY E. B. Berkenbueh.

ATTORNEY

UNITED STATES PATENT OFFICE.

WILLIAM L. GILCHRIST, OF ALBANY, OREGON.

BAG CLOSER.

Application filed April 4, 1921. Serial No. 458,409.

To all whom it may concern:

Be it hereby known that I, WILLIAM L. GILCHRIST, a citizen of the United States, and resident of Albany, in the county of 5 Linn and State of Oregon, have invented a new and useful Bag Closer, of which the following is a specification.

This invention relates more particularly to bags such as are used for tobacco, but it 10 is evident that it is equally applicable to bags for other uses.

The object of my invention is to provide an exceedingly simple and efficient means for opening or closing the mouth of a bag without requiring the use of more than one hand.

I accomplish this result in the manner set forth in the following specification and illustrated in the accompanying drawing, in which:

20 Figure 1 is a front elevation showing my device within an ordinary tobacco bag which is shown in dotted lines. Figure 2 is a side elevation of Fig. 1, and Figure 3 a plan. Figure 4 is a plan of my device showing the 25 manner in which it is operated by the thumb and forefinger.

Similar numbers of reference refer to the same or similar parts throughout the several views.

30 Referring in detail to the drawing, I have constructed my device of a U-shaped spring wire frame member 10 whose free ends are formed into the bends 11, 12, 13 and 14. The bends 11 serve as finger grips, while the 35 bends 13 form a hook for the draw string 15 of the bag 16. The bends 14 are used to finish the tips of the device and clamp the rim of the bag against the bends 12.

It will be evident that in order to open a 40 bag equipped with my device it is only necessary to press the bends 11 toward each other as shown in Figure 4. Releasing the pressure of these bends immediately closes

the bag opening, and the degree of tightness with which this closing is effected is determined by the amount of gathering formed at the opening of the bag.

It will be seen that the matter of adjusting this device to a bag is of itself a very simple matter, since it consists in nothing more than tying the draw string 15 to a size which is equal to the opening it is desired to have and then slipping the U-shaped member 10 down into the bag and slipping the opposite edges of the opening between 55 the bends 14 and the bends 12.

It will also be seen that for shipping purposes the bag can be filled as tightly as when any other method of closing is employed, inasmuch as the internal pressure of 60 the tobacco also increases the outward thrusts of the U-shaped member 10.

As all tobacco bags are sealed by a strip of paper tape it will be evident that there is no opportunity for tobacco to escape at 65 any time, unless so desired by the holder of the bag.

What I claim as new is:

A bag having a draw string tied at a smaller diameter than the diameter of the 70 bag in combination with a bag closing device consisting of a U-shaped spring-wire frame within said bag and whose upper ends are first bent inwardly and then outwardly in a manner to form a pair of hooks 75 having their openings toward the outside of said frame and adapted to receive the mouth of the bag from the inside, the ends of said hooks being then turned inwardly in a manner to clamp the shoulders of said bag, said 80 wire frame having a slight inward bend on each side below said hook portions adapted to receive the thumb and forefinger when compressing said frame which action causes the mouth of said bag to open.

WILLIAM L. GILCHRIST.
